APPARATUS FOR DEHYDRATING PETROLEUM PRODUCTS IN SITU IN TANK STORAGE

Edward P. Baker, New York, N. Y.

Application July 12, 1945, Serial No. 604,570

9 Claims. (Cl. 196—5)

1

This invention relates to storage tanks for storing petroleum products and other liquids which in their intended uses must be substantially free from water but tend to become contaminated with small but nevertheless objectionable amounts of water when stored in tanks of large volume. The invention has more particular application to such tanks set in the open and constructed of metal sheets or plates, and which are provided with a metal roof structure for preventing rain or snow from entering the tank.

In storing petroleum products in such tanks a certain amount of circulation of atmospheric air within the space between the stored body of oil or other liquid and the roof is usually unavoidable. Under certain conditions, condensation of water from the vapor within such space will occur on the inner surfaces of the roof structure and on the walls and other surfaces of the tank exposed to the atmosphere existing in such space and this water may drop from the structure or run down the surfaces into the liquid petroleum product and become entrained therein. The condensation may occur with changes in the weather producing a saturated condition of the water vapor in the air space above the liquid in the tank. For example, air which has entered the tank during a warm spell, replacing the contents of the tank or a portion thereof withdrawn for use, may contain a relatively large amount of moisture. Upon a fall of temperature of the atmospheric air the roof and the walls of the tank, particularly those constructed with metal, rapidly reduce in temperature and the vapor in contact therewith may be reduced to the dew point, so that condensation of water from the vapor readily takes place upon the roof and walls. Even in tanks which are filled to the normal level with the petroleum product the air in the space above the liquid level may contain or take up sufficient moisture in the normal movement of air to and from the space within the tank to produce condensation on the inner surfaces of the side walls and roof when these surfaces with which it is in contact become cooled. This condensation of water gives rise to the formation of droplets which will eventually grow in size or unite to form larger drops until their weight is sufficient to cause them to run down the walls of the tank or to drop from an under surface or a projecting portion of the wall or roof structure into the petroleum product within the tank.

Heretofore it has been regarded as practically unavoidable that petroleum products would pick up water in the manner above described in stor-

2

age, and it has been a more or less general practice in storing and handling heavier petroleum oils such as lubricating oils, fuel oils and the like, to heat the oil by means of steam coils immersed in the oil body in the tank. Usually this heating treatment will occur when it is desired to increase the fluidity of the oil preparatory to pumping it into tankers or tank cars for transport, but frequently such treatment must be carried on for a prolonged period before the moisture content of the oil has been reduced to the point where the required moisture tolerance specification is met. This is particularly true at certain times of the year and in colder climates as, for example, under winter conditions when the temperature outside the tank and of the exposed metal surfaces of the roof and adjacent side wall portions will be relatively low as compared with that required to drive the entrained mixture from the oil body. Under these conditions, the water vapor driven into the free space above the oil body has a great tendency to condense on the cooler surfaces of the roof and adjacent wall portions of the tank and to drip or run back into the oil body.

It is an object of the invention to prevent the condensate of water vapors which ordinarily forms in tanks in which petroleum products are stored from running down the surfaces thereof into or falling into the petroleum product within the tank from the roof or other parts of the tank structure.

It is another object of the invention to provide means for promoting and controlling the condensation of water vapors present in the ambient atmosphere within the tank and to collect the condensate and conduct it away to a place of disposal without remingling with the petroleum product.

An additional object is to provide means for controlling collection and disposal of the moisture driven off from a petroleum product during heating so as to prevent its reentrainment in the product.

A further object is to provide an improved and relatively inexpensive method of dehydrating petroleum products and other liquid that tend to take up or become contaminated with moisture in handling and storage.

In order to accomplish the above and other objects it is proposed according to the invention to provide means for inducing condensation within the vapor laden space above the petroleum product within the tank and beneath the roof structure thereof. This means may comprise a

plurality of members providing a condensation inducing structure enveloped by the water vapor within said space and extending generally horizontally, substantially completely across the internal cross-section of the tank. These members and this structure are made of heat conducting material and this structure is arranged in heat conducting relation to the tank structure or to other means for conducting heat from said members in order that these members shall be maintained at a temperature which will induce condensation on the surfaces thereof, including the under surface thereof, when the condition of the vapor in said space is such that condensation occurs on the roof and wall structure of the tank.

As tanks for the storage of petroleum products ordinarily are constructed with iron or steel plates for the tank walls and roof and with steel structural members for support thereof, in its preferred embodiment the invention utilizes as the condensation-inducing members metal sheets preferably of corrosion resisting material. These sheets are supported by the tank structure, and for the most part by the roof structure, by means of hangers or supports of heat conducting material, such as iron or steel rods or straps. These hangers or supports are fastened to the tank or to the roof structure as well as to the metal sheets of the condensation-inducing structure in heat conducting contact. As the condensation within a tank of the type to which the invention relates occurs for the most part when the atmospheric air is at a temperature low enough to reduce the temperature of the roof and adjacent wall portions of the tank to or below the dew point of the vapor within the space above the liquid within the tank, the provision of heat conducting connections and supports between the condensation-inducing structure and the tank structure ordinarily is sufficient also to reduce the temperature of this structure at least to the dew point and thus produce the condensation thereon. Within the scope of the invention any suitable means may be used for securing the requisite reduced temperature of the sheets or other members providing the condensing surfaces.

By arranging this condensation-inducing structure so as to extend substantially completely across the tank, condensation which is formed on the under side of roof of the tank or on its supporting structural members and which drips therefrom is intercepted. This condensation-inducing structure may be so formed and arranged in the space above the liquid level in the tank that the water thus dripping thereon may run downwardly along its upper surface, for example, toward the wall of the tank, and be collected or conducted to a place of disposal.

It is a further important feature of the invention that the under surfaces of the condensation-inducing structure, or appropriately associated sections thereof, are inclined to the horizontal sufficiently to cause any condensate formed thereon, to run sufficiently freely down this under surface under the action of gravity to insure that such condensate will not in its travel form into droplets of sufficient size to overcome the surface tension effect and drop off into the oil body beneath. The condensation-inducing structure may be made up of a plurality of sections which are of lengths, not exceeding a predetermined maximum length in the direction of the inclination of the under surface thereof, such that the moisture film and drops which collect on the under surface will flow along said under surface

while clinging thereto until the edge of said section is reached before dropping therefrom. Upon reaching this lower edge or other means providing a drip element adjacent the lower end of the predetermined length along which a drop travels down this inclined under surface before dropping from said surface, the drop together with any water running over said lower edge from the upper surface of said member will drip from said lower edge or from said drip element.

In order to prevent the water thus condensing upon the under surface of these sections and dripping from the lower edges thereof from falling into the petroleum product within the tank, the sections are arranged in overlapping relation with the lower edge of one section overlapping upon but spaced somewhat above the upper edge of the subjacent section. The water dripping from the lower edge of the superjacent section thus may fall upon the upper surface of the subjacent section and may run down this upper surface of this section toward the lower edge of the subjacent section. The water running upon the upper surfaces of said sections and carried successively thereover ultimately to the lower edge of the lowermost section of the condensation-inducing and conducting structure may drip from said lowermost edge into a collector, such as a gutter arranged therebeneath.

This arrangement of the sections in overlapping relation and with the lower edge of each section spaced above the upper edge of the subjacent section makes possible not only a simple construction, as will be apparent hereafter, but also provides space between the sections for the vapor within the vapor laden space to circulate between and to envelope the sections so as to come into contact with all of the exposed surfaces thereof. The condensation-inducing and conducting structure thus enveloped by the vapor, therefore, may be in contact with the vapor both at the under surface to which the condensate clings by surface tension and at the upper surface upon which the water dropping thereon from the roof structure, or condensed directly thereon from the vapor in contact therewith, may run toward the lowermost edge of said condensation-inducing and conducting structure. The spacing of the sections one above the other at the overlapping portions also must be sufficient to permit the drops which run on the under surfaces to reach the lower edge of the section of predetermined maximum length without touching the subjacent overlapped sections. If the drops were thus to touch said section the surface tension would cause them to pass around the edge to the under side of said subjacent section where by uniting with other drops they might increase their weight sufficiently to cause them to drop from said under surface into the petroleum product in the tank before running to the lower edge of the subjacent section.

A corollary feature of the invention is related to the feature above described of inducing formation of drops of such size as to run upon the under surfaces of the sections without dropping therefrom before reaching the lower edges thereof. In accordance with this corollary feature the under surfaces of said sections are formed with ridges, preferably ridges providing a rounded surface projecting downwardly therefrom, these ridges being arranged so that their lengths extend in the direction of the inclination of the under surfaces. The ridges preferably also extend parallel to each other and are of such size

and spacing in consideration of the inclination of the length of the ridge to the horizontal that moisture condensed thereon will become united into drops clinging only by surface tension to the under surfaces of these ridges and will run along the ridges toward the lower end of the section without dropping therefrom. Upon reaching the lower ends of the ridges the drops will drip therefrom onto the upper end portion of the section beneath.

Such ridged sections conveniently may be provided by corrugated sheet metal, preferably of the type providing rounded corrugations, the valleys between the ridges at the upper side of the sheet serving to conduct toward the lower edge of the sheet the water dropping thereon from the roof structure or condensed on the upper surface of the corrugated sheet. Such rounded ridges or corrugations also limit the amount of the condensation which will become united into drops because of the limited spacing between the ridges or corrugations. They furthermore prevent the water which is formed by the uniting of droplets and drops from becoming a stream running rapidly and somewhat irregularly over the surface and sometimes running into adjacent streams in the manner in which this may occur on a flat surface. The water therefore drips from the lower end of each member and from the lowermost member in a distributed manner.

In another aspect the invention provides a method for dehydrating petroleum products in storage. This process utilizes the step heretofore practiced of heating the petroleum, for example, by means of steam pipes placed within the body of the petroleum product within the tank. According to the process of the invention, however, this heating step may be carried on for a sufficient length of time to remove all or the desired amount of the moisture which may have become entrained in the petroleum product due to any of the conditions which have been described above. The heating may be carried on continuously for the requisite period to effect such removal and the process of the invention provides for continuous condensation and removal of the moisture thus driven off from the petroleum product and which passes up through the body of the product within the tank to the surface thereof to escape into the space between the said surface and the roof of the tank.

The condensation structure above described positioned in this space may be maintained by any suitable means at a temperature which will serve to condense on said structure the moisture thus driven into and filling this space by heating of the product in the tank. This structure also serves to prevent return, as by dropping from the roof structure and from the condensing structure itself, of the condensate which is formed thereon and upon the roof structure. The process of the invention, therefore, provides for dehydration of the liquid petroleum product by supplementing the heating step by the further steps of condensing the moisture driven off by heating and of conducting the condensate away from the vapor laden space to a place of disposal under the action of gravity but also under the control which utilizes surface tension for maintaining the condensate clinging to the under surface of the condensing structure as it runs on said under surface. The dehydration of the petroleum product while it is in storage in the tank, therefore, may be accomplished with-

out the necessity of removal of the product by pumping to special dehydrating apparatus. The process, therefore, may be carried out at any convenient time during the period of storage preparatory to removal of the product from the tank.

Other objects and features of the invention will be understood from the description to follow of the drawings in which

- 10 Fig. 1 is a plan view taken on line 1—1 of Fig. 2 showing an embodiment of the invention which utilizes a plurality annular radially overlapping sections made up of corrugated sheet metal to provide the condensation-inducing and conducting structure;

- 35 Fig. 10 is a section on line 10—10 of Fig. 7; and
- Fig. 11 is a plan view of another modification of the structure of the invention.
- In Figs. 1 and 2 the condensation-inducing and conducting structure is provided by sheets 1, 2 and 3 of corrugated sheet steel which preferably is galvanized in order to resist rusting. These sheets are arranged in overlapping arrangement as may be seen in Fig. 2 and are inclined to the horizontal so that condensate falling thereon from the roof will run toward the lower edge of each sheet. Condensate falling on the uppermost sheet 3 will drip from the lower edge 5 thereof upon the upper surface of the middle sheet 2 and will run on its upper surface, together with condensate falling directly thereon, toward the lower edge 7 of sheet 2 from which it will drip upon the upper surface of sheet 1. The water thus brought together from the sheets 2 and 3 will run upon the upper surface of sheet 1, together with water which may have dropped directly on sheet 1 from the roof 11 or the supporting beams 12 thereof, and will drip from the lower edge 9 of sheet 1. Adjacent the tank wall 13 a gutter 15 is supported to receive the drip from the lower edge of sheet 1.
- For support of the sheets 1, 2 and 3, a channel beam 17 may be erected within the tank and supported by suitable means adjacent the tank wall and upon a collar 45 supported on the central support 19 commonly used in such a tank structure for support of the roof beams 12. Hangers 21, depending from channel 17 adjacent the lower end of each of the sheets 1, 2 and 3 and also adjacent the upper end of the sheet 3, are provided. These hangers are fastened by bolts 22 to the channel beam 17 and are also fastened by bolts 25 to the smaller cross channels 27. These cross channels are fastened by means of bolts 29 to the sheets 1, 2 and 3 adjacent the lower ends thereof. In the embodiment

ment being described the corrugations 31 of the sheets 1, 2 and 3, extend generally radially in the direction from the central support 19 toward the wall of the tank and symmetrically with respect to the adjacent radially positioned channel beams 17, as shown in dotted lines in Fig. 1. The assembled sheets 1, 2 and 3 form sectors the edges of which are substantially in the vertical planes of the channel members 17.

These radial edges of the sectors, as will be noted from Fig. 1, cut diagonally across the corrugations of the sheets 1, 2 and 3. There is thus formed no continuous straight edge along these radially extending edges of the sheets and of the sector assembly formed by these sheets 1, 2 and 3 in their overlapping arrangement. Water, therefore, which as drops might tend to drip from such a continuous straight edge, by running along the inclination of such an edge and uniting with other drops until they become heavy enough to fall from such an edge, is prevented from doing so because it may only run to the low point of each of the corrugations crossed by the diagonally extending edge. Thus, as may be seen in Fig. 3, any water falling on the upper sides of the sheets 1, 2, or 3 in the right-hand sector shown in this figure, instead of dripping from the edge 33 will merely run along this edge until it reaches the next lowest point in the corrugation. Here it may pass around to the under side of the sheet by surface tension and then be carried to the lower edge 5, 7 or 9 as the case may be, of the sheet from which it falls onto the next lower sheet in the series or into gutter 15. Thus, although the radially extending edges of the sectors in the embodiment illustrated in Figs. 1 and 2 do not overlap but merely are in adjacent relation as shown in Fig. 3, there will be no leakage of water through the condensation-inducing structure of the invention which may fall into the petroleum product stored in the tank.

It will be clear from the details shown in Figs. 2, 4 and 5 and from the relation of the sheets 1, 2 and 3 shown in Fig. 2, that each of said sheets in the portion where it overlaps the subjacent sheet is vertically spaced from said subjacent sheet. For this purpose spacers 35, which may be made of pipe of suitable size to fit around bolts 29, are placed between the two overlapping sheets 1 and 2 for example in Fig. 3. These spacers 35 hold the sheets apart when the bolt 29 is inserted through the lower flange 37 of the channel member 27 and the sheets 1 and 2 are fastened in place in such spaced relation by means of the nut 30 running on the lower end of the bolt 29. The spacing of the sheets 1 and 2 and of the sheets 2 and 3 provides passages for vapors driven off from the oil body when it is heated to escape from the space beneath the condensate-collecting and conducting structure to the space between the roof structure 14 and 12 and such condensate-collecting and conducting structure. In this way the vapors evolved from the oil body not only are readily contacted with and subjected to the condensing action of the cooler surfaces of each of the sheets 1, 2 and 3, but are also enabled to come into contact with the surfaces of the roof, which will usually be still colder under weather conditions when the problem of drying petroleum products is most acute.

In the embodiments illustrated it has been assumed that the tank would have a diameter of about 35'. Additional annular sections of sheets will be provided for larger diameter tanks. Having regard to the inclination of the sheets 1, 2

and 3 necessary to produce the desired movement of the water thereon under the action of gravity, the vertical spacing of the overlapping portions of the sheets may be about 2" when utilizing corrugated metal sheets having a depth of corrugation of about $\frac{5}{8}$ ". Such dimensions are merely indicative and may be varied to suit practical conditions provided the spacing may be sufficient for ample circulation of the vapors evolved from the liquid being stored.

To hold the sector assemblies of the sheets 1, 2 and 3 in proper relation to each other a strap 40 may be formed with a slight bend to conform to the positions of the two channels 27 of adjacent sectors as shown in Fig. 5. The bolt 25 for fastening the hanger 21 to the channel 27 may also pass through this strap 40, all of the engaging parts being fastened together by said bolt and its nut 26. In order to provide a rigid connection and to prevent movement of the sectors relative to each other two bolts 41 and 42 are used to fasten the opposite end of the strap 40 to the adjacent channel 27. The hanger 21 thus may act to support the adjacent ends of both of said channels in two adjacent sectors. As will be seen in Fig. 1, therefore, only one hanger 21 is utilized in the embodiment being described for suspension from each of the channels 17 which extend radially from the central support.

By means of said bolts 25, 41 and 42 and the strap 40 as well as the hanger 21 and its fastening bolt 22, good heat conducting contact may be secured between the channels 27 and the supporting radial channels 17. These channels 17 may be supported at the ends thereof in good heat conducting contact with the tank structure or, if necessary, by additional connections between said channels 17 and the roof structure to insure heat transmission by conduction between the channel 17 and the wall and roof structure. The bolts 29 and the spacers 35 serve to hold the sheets 1, 2 and 3 in good heat conducting contact with the supporting channel members 27 so that the heat may be conducted from the sheets 1, 2 and 3 through said channels 27 and the hangers 21 to the roof structure. As many bolts and spacers may be provided intermediate the ends of the channels 27 as are required to hold the sheets in good contact with said channels and to prevent sagging of the sheets in their width. Other expedients may be adopted if required for producing good heat conducting contact, such as shaping the ends of the spacers to conform to the corrugations of the sheets and providing washers for the nuts 30 which also conform to these corrugations. Ordinarily the connections between the parts will be sufficient to provide for the requisite heat conduction.

The lower end 9 of the sheet 1 is spaced somewhat from the tank wall so as to permit the water running upon the upper and under surfaces of the sheet 1 to drip into the gutter 15 mounted on the wall 13 of the tank. As the sheets 1, 2 and 3 are of corrugated form, the corrugations provide a plurality of valleys for conducting the water freely beneath the lower flanges of the channels 27. The gutter 15 is made substantially watertight to the wall of the tank 13 so as also to collect condensate which may form on and run down the tank wall. This gutter may also be provided with a slope in one direction or the other or both directions circumferentially of the tank for conducting the water to drain pipes 16 which may be placed adjacent the columns 14 which are part of

the tank construction for stiffening and supporting the tank wall. The pipes 16 may lead the collected water to a suitable place of disposal outside of the tank.

Adjacent the central supporting column 19 the radially extending channels 17 are supported on a collar 45, which for convenience may be formed in two parts as shown in Fig. 6, extending about the column 19 and fastened thereto by suitable means such as tap bolts threaded in the column wall. As shown in Fig. 6 the collar 45 may be insulated from the column 19 by a ring 47 of suitable insulating material in order to prevent conduction of heat from the column 19 through the channels 17 to the roof structure. Insulating pads 43 also may be provided at the top of the column 19 between the beams 12 and said column, to prevent or limit the conduction of heat from the column directly to the roof structure. By thus insulating the column 19 from the channels 17 and from the roof the column 19 may be maintained more nearly at the temperature of the petroleum product within the tank and not become reduced to the dew point temperature of the vapor in the space above the petroleum product. Condensation on said column itself, therefore, may be prevented or reduced, thus avoiding the necessity of collecting of such condensate from the surface of the column 19.

It is to be understood, however, that the provision of insulation between the column 19 and the supporting ring 45 and between the head of the column 19 and the roof beam is optional. If such insulation is omitted the column may act, to some extent at least, as a condensing surface because of heat transfer between the column and the roof. In such case, the ring 45 may act to catch any condensate formed on the column and direct it to the upper surfaces of the adjacent sheets 3 or 61.

The inclination of the sheets to the horizontal must, of course, be sufficient to insure that the water condensed on the surface will be caused to run down along such surface sufficiently rapidly to be carried to the lower edge of each sheet before it has formed into drops of such size as to overcome the surface tension effect and drop off into the stored liquid. The minimum angle of inclination of the sheets that may be employed without risk of the undesired dripping of the condensate from the under surface of the sheets, will vary with the character of the metal surface and with the length of the sheet. The requisite inclination for a sheet of a given kind, say plain stainless steel, aluminum, or ordinary galvanized iron sheets, for a given length of the sheet may be determined by making suitable preliminary tests simulating actual conditions as they will exist in the storage tank.

As previously stated, it is preferred to use corrugated sheets because the corrugations serve to direct the condensate to the lower portions of the corrugations whence they will travel more freely along the sheets to the lower edge and then fall onto the upper surface of the next lower sheet or into the peripheral trough as the case may be.

It is desirable to maintain the radial inclination of the sheets as low as is consistent with the proper flow of the condensate along the sheets without dripping off, since in this way the amount of space taken up vertically in the upper portion of the tank by the condensation-inducing and conducting structure is minimized. By way

of example, by using galvanized iron or steel having corrugations of standard depth of about $\frac{5}{8}$ ", I have found that if corrugated sheets of 6' in length are disposed at an inclination of about $7\frac{1}{2}^{\circ}$ to the horizontal there will be no substantial dripping of the condensate collecting on the under surface thereof until it reaches the lower edge of the sheet where it is intended that it shall drop off on the next adjacent lower sheet. This inclination was adopted in anticipation that there would be a greater tendency for the condensate to drip off after the structure has been installed for some time, due to corrosion effects or other influences affecting the smoothness of the surface of the sheet. On new corrugated galvanized sheet material an inclination to the horizontal of 4° has been found adequate to insure the desired flow for the full length of sheets 6' in length.

In Figs. 7 and 8 is shown a modified arrangement of corrugated sheets to provide the condensation-inducing and conducting structure of the invention. This modification permits the use for the most part of rectangular sheets having dimensions in which such sheets are commonly manufactured. The supports for these sheets may be arranged similarly to the arrangement shown in Figs. 1 to 5. In this embodiment, however, the assembly of the sheets is shown supported directly from the roof beams of the tank without the intervention of an additional supporting member, such as the channel 17 shown in Figs. 2, 3 and 4. In Fig. 7 the radially extending broken lines represent the positions of the roof beams 60 in the roof structure, one end of each beam resting upon structural member 61 extending circumferentially along the wall of the tank adjacent the top thereof. The other end of the beam 60 which, as may be seen above the column 19 may be of channel section, bears upon the upper end of the column 19. An insulating pad 48 may be provided to prevent or reduce conduction of heat from the column 19 to the beams 60.

In this embodiment the members 63, 64 and 65 are positioned in tiers each consisting of a plurality of rectangular sheets of corrugated sheet steel arranged in each tier with the lengthwise edges thereof in overlapping nesting relation as shown in Fig. 10. Adjacent the lower end of each tier and extending along the transverse lower edge of each sheet the channels 27 may be fastened to the sheets 63, 64 and 65 in the same manner as provided in the construction of Figs. 1 and 2. The sectional view shown in Fig. 4 to enlarged scale represents the arrangement of the channels 27 in relation to the overlapping sheets 63, 64 and 64, 65, in which the spacers 35 and the bolts 29 with their nuts 39 hold the sheets 63, 64 and 65 in the requisite vertically spaced relation. The hangers 26 may be fastened at their lower ends to the channels 27 in the construction shown in Figs. 7 and 8 by means of the bolts 25 and may be fastened at their upper ends to the supporting roof beam 60 by means of bolts 22 in the same manner as in Figs. 1 and 2.

The channel 27 adjacent the lower end of the lowermost member 63 may be positioned with respect to the lower edge 67 of said member 63 so as to extend across the chord of the circular arc formed by the edges of the sheet 63 in the assembled structure as shown in Fig. 7. Where the column 14 positioned at the wall of the tank would interfere with the channel 27 adjacent

the lower edge of the sheet 63, this channel 69, as shown in Fig. 7, may be kept back from said lower edge to clear the column 14. The sheet or sheets 63 adjacent such column 14 may be cut to clear said column in order that the water passing over the lower edge 67 thereof may fall clear of the column 14 so as to prevent the water running down said column into the petroleum product. The gutter 15 which is provided beneath the lower edge 67 of the lowermost sheets may be formed at the column 14 to receive the portion of the condensate which drips from this portion of the lower edge 67. As in the arrangement of Figs. 1-5 the water running in the valleys on the upper surfaces of the lowermost sheets 63 when of corrugated form may pass under the lowermost channel 27 or 69 without obstruction.

Adjacent the diameter of the tank, that is, beneath two oppositely extending roof beams 60, shown on the vertical center line in Fig. 7, a pair of channels 71, 72 may be arranged to which respectively are fastened by bolts 73 the upper ends of the uppermost tiers of sheets 65. These channel members 71 and 72, as shown in Fig. 9, may be bolted together by bolt 75 passing also through the hanger 76 which is fastened to the channel beam 60 immediately above by bolt 77. By means of the bolts 73 and suitable washers, if needed, the sheets 65 may be held in good heat conducting relation with the channels 71 and 72 and with the hanger 76 and the roof beams 60. As many bolts 73 as are requisite to hold the sheets 65 in good contact with channels 71, 72 while providing adequate support for said sheets may be used. Depending upon the size of the channels 71 and 72 a greater or less number of the hangers 76 may be used having regard also to the provision of heat conducting members connecting to the roof to effect reduction of the temperature of the sheets 65 as described in connection with Figs. 1 and 2.

The channels 27 in the embodiment being described may be of such size that the hangers 21 may be provided at the points where the channels 27 pass immediately beneath the beam 60, or at alternate points as may be seen in Fig. 7. In this Fig. 7 these hangers 21 are shown connected to the respective beams 60 in one half of the extent of the condensation-inducing structure. Those hangers 21 which support the members 27, 69 which are adjacent the wall of the tank may be connected to each of the radially extending beams 60. The channels 27, 69 in the arrangement shown in Fig. 7 for the most part extend across two of the corrugated sheets 63 transversely to the corrugations thereof and may be of such section as to support these two sheets upon a single hanger 21, the straps 40, as shown in Figs. 3, 4 and 5, serving in this construction also to join adjacent sections supported by channels 27 so as to produce a rigid structure and to transfer the load to the hangers 21. The channels 27 extending along the lower edges of sheets 64 and 65 may be of any suitable length and may be joined by straps similar to the straps 40.

As in the construction shown in Figs. 1 and 2, the gutter 15 may extend between the columns 14 and may be connected to drain pipes 16 adjacent said columns for conducting away the condensate in the same manner as described in connection with Fig. 1.

In Fig. 11 another modification of the condensation-inducing and conducting structure of the invention is shown in diagrammatic outline.

Between the central column 19 and the wall of the tank sectors 80 of sheet metal of appropriate sector size, approximately 90° in the example shown, may be supported by hangers 82 which 5 may be fastened to the supporting beams of the tank in any suitable manner to produce a rigid support. As in the embodiments previously described sectors 80 are constructed with individual sheets or tiers 84, 85, 86, each of which 10 has a radial dimension of a predetermined maximum length similar to the length of the sheets 1, 2, 3, 63, 64, 65, so as to prevent water dropping from the underside thereof before reaching the lower edge 87 of each sheet. Each of the sheets 15 84, 85, 86 is arranged inclined downwardly to the wall of the tank and with its lower edge in overlapping relation to the subjacent sheet, so that water dripping from the lower edges 87 may fall upon the subjacent sheet or tier and be carried 20 over the upper surface thereof to the adjacent sheet or tier. A gutter 89 may be provided to catch the drip from the lowermost edge of the sheets adjacent the tank wall, as in the embodiments previously described.

25 In the embodiment of Fig. 11, the lateral edges 91, 93 are shown in overlapping relation. Means 30 may be provided for vertically spacing the sectors at their overlapping lateral edges, as well as at their lower edges 87 with respect to the upper edges of the subjacent sheets, to provide 35 for passage of the vapors between the sheets and sectors so that it may come into contact with both the upper and lower surfaces thereof. The overlapping arrangement of the lateral edges 91, 93 prevents condensate falling from the roof of the tank from reaching the petroleum product in the tank. The arrangement of the sectors and sheets with all edges overlapping and extending substantially completely across the cross-section 40 of the tank is advantageous where the sheets are smooth, that is not provided with ridges running in the direction of the inclination. The construction shown in Fig. 11 also may be advantageous where it is inconvenient to support 45 corrugated sheets in the manner described in the previous embodiments or where because of availability of materials or for other reasons plain sheets, that is, those without corrugations or other fabricated form, may be used to greater advantage.

50 By providing the usual heating coils placed within the body of the petroleum product within the tank and supplying them with a heating medium such as steam, dehydration of the product 55 may be accomplished while the product remains in the tank. Vapor of water driven off from the product by such heating into the space above the product and beneath the roof structure may be condensed not merely on the roof structure but upon the sheets 1, 2, 3, 63, 64 and 65 and the condensate may be removed from said space substantially as fast as it is driven off into such space. The apparatus of the invention, therefore, makes it possible to dehydrate petroleum products while 60 they are in storage without removal thereof to special apparatus and without special mechanically operated equipment installed in connection with the tank. The stationary structure which the invention utilizes having no moving parts and 65 requiring no motive power makes possible the improvement of the quality of the petroleum product without the cost of operating such special equipment.

70 While the structure embodying the invention has been described in its preferred forms as par-

ticularly designed to act both as a condensation-inducing structure and as a condensate-collecting structure, it will be understood that the condensate collecting features of the invention may be used without taking the special steps recommended to insure that the structure will also act to cool the vapors coming into contact with it and thereby cause their condensation. While the structure will normally be cooled, to a greater or less extent, because of the heat conductivity of the connections with the roof and adjacent side wall surfaces of the tank, when the outside atmosphere is cooler than the ambient atmosphere within the tank, nevertheless, it is a great advantage in the storage and handling of petroleum products to insure the collection and removal of the water condensed on the under side of the roof and the adjacent wall surfaces from the air entering the tank in the normal "breathing" circulation of air between the atmosphere and the interior of the tank.

Although the invention has been heretofore described with particular reference to its use in the storing and handling of petroleum and petroleum products, it will be understood that it has many other applications where liquids, either wholly or partially non-miscible with water, are stored in large tanks normally having constant or intermittent communication with the atmosphere or from which it is desired to drive off water that has become mixed therewith.

Various modifications of the constructions described, particularly of the details for supporting the condensation-inducing and conducting structure, may be used to suit particular conditions while affording the requisite features of the invention. Therefore, the invention is not to be deemed as limited, otherwise than as indicated by the appended claims.

I claim:

1. In a storage tank for heavy liquids such as petroleum products of low volatility having an enclosing wall and a metal roof structure separating the atmospheric air from the space within the tank, the combination therewith of a plurality of sheets of heat conducting material of predetermined maximum length supported within said space beneath said roof structure with their lengths inclined to the horizontal and with the lower edge portions thereof in overlapping and vertically spaced relation to the upper edge portions of the sheets subjacent thereto to provide a condensation-inducing and conducting structure extending generally horizontally substantially completely across the internal cross section of said tank, means providing a heat conducting connection from said sheets to the tank structure to maintain said sheets at a temperature inducing condensation thereon of water vapor present in said space when condensation of such vapor occurs on said roof, the inclination of said sheets being sufficient to cause the water condensed on the under surface thereof to run on said under surface toward the lower edges thereof while clinging to said under surface by surface tension, said sheets providing at their undersurface thereof a plurality of downwardly projecting rounded ridges each running in the direction of the inclination of the sheets and spaced apart transversely of said direction of inclination, said spacing and the length of the sheets being predetermined in relation to the inclination of said sheets to provide for accumulating and conducting to said lower edge of each sheet an amount of condensed water which will run upon the

undersurface of each ridge and cling thereto by surface tension without dropping therefrom before reaching said lower edge of the sheets and will drip from said lower edge upon the upper surface of the subjacent sheet, each of said sheets having its upper surface formed so as to conduct to its lower edge the water condensed on or falling thereon, and means for collecting and conducting to a place of disposal the water dripping from the lower edge of the lowermost sheet.

2. In a storage tank for heavy liquids such as petroleum products of low volatility having an enclosing wall and a metal roof structure separating the atmospheric air from the space within the tank, the combination therewith of a plurality of sheets of corrugated sheet metal arranged with their edge portions adjacent each other within said space beneath said roof structure to provide a condensation-inducing and conducting structure extending generally horizontally substantially completely across the internal cross section of said tank, said sheets being positioned in said condensation-inducing and conducting structure with the lengthwise extent of the corrugations inclined to the horizontal and with the lower edges of said sheets transverse to the corrugations overlapping and spaced vertically above the upper edges of the subjacent sheets, means for supporting said condensation-inducing and conducting structure in heat conducting relation to said tank structure to maintain said sheets at a temperature inducing condensation thereon when condensation occurs on said roof, the size of and spacing between the corrugations in each sheet, the inclination of said sheets and the maximum lengthwise extent of the corrugations running to the transverse lower edges thereof being such that water condensed on the under surface of each of said sheets will collect and run along and upon the under surface of each downwardly extending corrugation ridge to said transverse lower edge and will drip from said edge upon the next subjacent overlapped sheet without dropping from said ridge before reaching said edge, said vertical spacing of said overlapping edges being sufficient to prevent contact of said water running on said ridge with the subjacent sheet before reaching said lower edge.

3. In the combination with a storage tank according to claim 2 in which the roof structure of said tank comprises structural members for support thereof extending radially from a central support toward the tank wall, said sheets being arranged with the corrugations running downwardly in the direction from said central support and generally radially of the sectors formed between each two adjacent radially extending structural supporting members, the assembly of said sheets being formed with lateral edges extending radially and diagonally across the corrugations to form sectors substantially of the same size and shape as the sectors between said roof supporting members, and means for supporting said sector assemblies with said lateral edges thereof closely adjacent each other, whereby condensation dropping on the sheets of said assembly is prevented from passing therebetween.

4. In the combination with a storage tank according to claim 2, said sheets being of rectangular form and arranged in tiers with the adjacent transverse edges of the tiers in said overlapping vertically spaced relation and with the corrugations of the sheets of each tier at the lengthwise

edges thereof in interfitting overlapping relation.

5. In the combination with a storage tank according to claim 2, spacers between said sheets at said overlapping vertically spaced transverse edges, and means cooperating with said spacers to support both said sheets in said vertically spaced relation.

6. In the combination with a storage tank according to claim 2, a metal structural member in heat conducting relation to and extending transversely of the corrugations of a superjacent sheet adjacent said lower transverse edge thereof which overlaps the subjacent sheet and connected to both of said sheets for support thereof, and a metal hanger providing a heat conducting connection between said structural member and said roof structure and supporting said structural member to support said sheets in said condensation-inducing structure.

7. In the combination with a storage tank according to claim 2 in which the roof structure of said tank comprises structural members for support thereof extending radially from a central support toward the tank wall, said sheets being arranged with the corrugations running downwardly in the direction from said central support and generally radially of the sector formed between two of said radially extending structural supporting members, the assembly of said sheets being formed with lateral edges extending radially and diagonally across the corrugations to form sectors substantially of the same size and shape as the sectors between said roof supporting members, means for supporting said sector assemblies with said lateral edges thereof closely adjacent each other, whereby condensation dropping on said assemblies is prevented from passing therebetween, and a collar extending about said central support in heat insulating relation thereto for supporting the ends of the sector assemblies adjacent the central support, said sector assemblies being arranged in relation to said central support to receive therefrom condensate forming on said central support.

8. In the combination with the storage tank according to claim 2, said tank being of circular horizontal cross-section, means for collecting and conducting to a place of disposal the water dripping from the lower edge of the lowermost sheet in said condensation-inducing structure, said means comprising a gutter extending generally horizontally along and conforming substantially to the arc of said tank wall, said lowermost sheets having the lower edges thereof extending above said gutter substantially parallel to but spaced from said tank wall, said means for supporting said condensation-inducing structure in-

cluding a straight member supported with its ends adjacent said wall and positioned substantially in the chord of the arc of said wall and supporting said lowermost sheets with their lower edges in said parallel relation to said tank wall.

9. In the combination with a storage tank according to claim 2 in which the roof structure of said tank comprises structural members for support thereof extending radially from a central support toward the tank wall, said sheets being arranged with the corrugations running downwardly in the direction from said central support and generally radially of the sector formed between two radially extended supporting members, the assembly of said sheets being formed with lateral edges extending radially and diagonally across the corrugations to form sectors substantially of the same size and shape as the sectors between said roof supporting members, means for supporting said sector assemblies with said lateral edges thereof closely adjacent each other, whereby condensation dropping on said assemblies is prevented from passing therebetween, said means for supporting said condensation-inducing and conducting structure including a member adjacent the wall of the tank and extending substantially in the chord of the arc of the sector formed between two radially extending roof supporting members, the edges of said sector assembly adjacent said tank wall being parallel to and spaced from said tank wall, whereby the water conducted to the lowermost edge of said assemblies adjacent said tank wall will drip therefrom between said chordal supporting member and said wall, and means for receiving and conducting away to a place of disposal the water dripping from said lowermost edge.

Certificate of Correction

Patent No. 2,460,271.

February 1, 1949.

EDWARD P. BAKER

It is hereby certified that error appears in the printed specification of the above numbered patent requiring correction as follows:

Column 13, line 66, claim 1, for the word "their" read *said*;
and that the said Letters Patent should be read with this correction therein that the same may conform to the record of the case in the Patent Office.

Signed and sealed this 13th day of September, A. D. 1949.

[SEAL]

JOE E. DANIELS,
Assistant Commissioner of Patents.
